UNITED STATES PATENT OFFICE.

DAVID GRAVEL, OF CHATTANOOGA, TENNESSEE, ASSIGNOR TO STANDARD-COOSA-THATCHER COMPANY, OF CHATTANOOGA, TENNESSEE, A CORPORATION OF TENNESSEE.

SINGEING WARPING MACHINE.

Application filed March 19, 1925. Serial No. 16,788.

My invention relates to singeing and warping machines, and it is an object of the invention to provide a machine of this character, by which satisfactory work may be done in spite of the necessary stops and starts due to broken yarns. In such operations as ordinarily conducted the operation of the burner is discontinued a little before the yarn travel ceases so as to avoid damage to the yarn, and is resumed a little after the travel of the yarn begins, for the same reason. As a result of this, there are spaces along the yarn several yards in length where the yarn is unsinged, or where the singeing or gassing is incomplete. My invention seeks to provide a machine free from these defects.

Another object of the invention is to provide effective locking means to prevent operation of the burners until after the starting of the parts of the machine by which the yarn is caused to travel.

Still another object is to provide improved stopping means operable by failure of a yarn.

Referring to the accompanying drawings, which are made a part hereof and on which similar reference characters indicate similar parts,

Figure 1 is a side elevation of a machine embodying my invention,

Figure 2 is a side elevation on a larger scale, of a part of the mechanism shown in Fig. 1,

Figure 3 is a wiring diagram,

Figure 4, a side elevation at the opposite side of Fig. 2,

Figure 5, a longitudinal section of parts shown in Fig. 4, but with the parts in different position,

Figure 6, a side elevation of parts of the stop mechanism when the machine is in operation,

Figure 7, a view similar to Fig. 6, showing the parts in intermediate position,

Figure 8, a view similar to Fig. 6, showing the parts in idle position after the machine has been stopped,

Figure 8^a, a section on line 8^a—8^a of Fig. 8,

Figure 9, an end elevation on an enlarged

scale of a fragment of the gas distributing connections shown in Fig. 4,

Figure 10, a side elevation of the parts shown in Fig. 9,

Figure 11, a plan view of the parts shown in Figs. 9 and 10, and

Figure 12 is a plan view similar to 11, but showing the parts in a different position.

In the drawings, reference character 19 indicates a creel containing a plurality of cheeses 20 having yarns wound thereon, which cheeses are supported on spindles, the yarns being drawn off axially and passing through guides indicated at 21. From the guides 21 the yarns pass to a comb 22, thence over a bank of burners 23, a rod 24, a guide roller 25 of substantial size, back over a second bank of burners 26, over a large roller 27, a smaller roller 28 to a gathering device 29, and thence to a balling machine 30 driven by a motor 31. The motor is connected to the balling machine by a belt 32 operated by a belt shifting device 33 which shifting device is connected by a link 34 to a lever 72 connected to a foot lever 35 which is the control lever for the gassing and driving mechanism, and it is provided at its outer end (Figs. 4 and 5) with a counter weight 36 and a rod 37 mounted loosely in an opening in the counter weight. At the lower end of the rod is a head 38 and between the head and the weight is a spring 39 for cushioning the movement of the control lever in one direction. The other end of the lever 35 is provided with a foot tread to which is attached a link 40. This link is connected at its upper end to a vertical bar 41 which has a cam face 42 at its upper end. The bar is guided for vertical movement by brackets on the machine frame. A three-armed rocker is pivoted at 43 on the frame, the said rocker having a slotted arm with a pin 44 adjustably mounted in the slot, the pin 44 co-operating with the cam face 42 on the upper end of the bar 41 to move the rocker counter clockwise as shown in dotted lines in Fig. 2. The arm 45 extends rearwardly from the pivot of the rocker and is weighted to move the rocker clockwise into the full line position shown in Fig. 2. A

spring pressed pin 46 is mounted for vertical sliding movement in the third arm of the rocker arm. When the rocker arm is held in the position indicated in Fig. 2 by means 5 of the bar 41, the pin 46 engages a notch in the upper side of a bar 47 which bar is mounted to slide horizontally in guides on the machine frame. It will be obvious that the pin 46 engaging the notch in the upper 10 side of the bar 47 prevents longitudinal movement of this bar when the control lever 35 is in the idle position. The bar 47 (Fig. 2) is provided at its inner side with a guide lug 48 for a rod 49. A pair of springs 50 15 are supported on the rod 49 at opposite sides of the guide lug 48, each spring being supported between a lug and a buffer block 51, carried by the rod, said blocks abutting against the ends of the springs. When the 20 bar 47 is moved in either direction one of the abutting blocks 51 abuts against the frame 61 of the machine. It will be seen from consideration of Fig. 5, that longitudinal movement of the bar 47 in either direction will 25 be cushioned by one of the springs 50. The bar 47 is moved endwise by a hand lever 52 fixed to a shaft 51', the hand lever being pivotally attached at 52' to a link 53 which latter is pivotally secured at one end to a 30 bar 55 and has a pivot 54 at its other end. The bar 55 is pivotally connected to a pair of rock arms 56 hereinafter described. The bar 57 above the bar 47 is connected to it by a link 58 pivoted at 54 to the link 53 and 35 pivotally attached to the bar 57 at 58'. The bar 57 is pivotally connected to a series of rock arms 59 similar to rock arms 56. It will be seen that the hand lever 52 and the bar 47 have extreme positions but no intermediate position, wherefore one or the other 40 of the springs 50 will always be compressed as shown in Fig. 5 and will thus be of assistance in starting the movement of the hand lever and the parts connected thereto. The 45 rock arms 56 and 59 are connected to the respective burners 26 and 23 by means of pipes 60 extending across the frame work 61 on which the gassing devices are supported. The means for supplying gas to these 50 pipes as indicated in Figs. 4 and 9 to 12 consists of conventional piping including upright sections 62 leading to valves having casings 63 in which the pipes 60 are mounted to oscillate. Rotation of the burner supporting pipes from the position of Fig. 12 to 55 that of Fig. 11 cuts off the flow of gas. Pin 64 in the pipes limits the rotating movement of the pipe. A pilot light 65 is mounted in a rim 66 fixed to each pipe section 60 in such a way as to hold the pilot light always 60 in alignment with burners 23. The pipe sections 67 are connected to oscillate with pipe sections 60 and at their outer ends are connected to globe valves 68, said valves 65 being supported pivotally by valve stems 68'

fixed to valve casing 63 in a manner so as to permit oscillation of each pipe section 67 with its section 60. The globe valves 68 are connected to the main supply pipes by pipes 69. The passages of such pipes to 70 the pilot device being always open except as they may be interrupted by means of the hand operated valve 70. It will be evident from the foregoing description that the flame on the pilot burners will remain when 75 the other burners are turned off, so that the gassing action may be resumed immediately on returning the burners to the working position where they will be at once relit by the pilot burners. 80

The elements of the stopping mechanism shown in Figs. 6 to 8 inclusive include a rock arm 71 mounted on a shaft 51'. The rock arm 71 is connected to an arm 72 by means of a link 73. The arm 72 is fixed to 85 the control lever 35. The end of the link 73 adjacent the arm 72 is slotted and is connected to the arm 72 by a pin which moves in this slot, whereby the rock arm 71 and the arm 72 may have considerable movement independent of each other, but must move together after such independent movement. An object of this construction is to permit the weight 36 to have more effective action 90 under certain circumstances. To the rock 95 arm 72 also is attached the link 34 which operates the belt shifter 33 as previously described. A latch 74 is pivoted at 75 and this latch has a tooth 76 (Fig. 8) for engagement with the front face of the lateral projection 71' on the rock arm 71, whereby the rock arm is held in the position of Fig. 6 when the parts of the machine are in action. A detent 77 is also pivoted at 75, this detent having integral therewith or fixed thereto a 100 weighted arm 78 carrying a pin 79 for disengaging the latch 74 from the rock arm 71. A third arm 80 is made integral with or fixed to the arm 78 and the detent 77. The arm 80 is connected by a link 81 to the armature 82 105 of an electro-magnet 83 in a circuit 84 which circuit is always energized so that the armature is always attracted to the electro-magnet and tends to hold the parts in the position of Fig. 6, the weight of the weighted 110 arm 78 being so great however that it will overcome the effect of the electro-magnet when the detent 77 is released. Another 115 electro-magnet 85 is connected in a circuit normally open and indicated at 86 (Fig. 3). An armature is provided at 90 for the electro-magnet 85, and this armature is carried by a pivoted trigger arm 91. An arm 92 in which the armature 82 is supported is pivoted coincidently with arm 91, 120 the arm 92 being provided with a pair of fingers between which the end of the arm 91 extends. The detent 77 engages a notch in the lower edge of the trigger 91 by which it is held. The permanent magnet 125

83 is not strong enough to support the arm 78 alone but co-operates with the detent arm 77 to support this arm. The magnet 83 tending to hold up the arm 78 relieves the detent 5 from having to sustain the whole weight of the arm 78. If the full weight of the arm 78 were supported on the detent 77 it would require a stronger pull to lift the trigger arm 91. It is desired that this arm be released with only a slight pull by the magnet 85.

Fig. 3 shows one of a series of wooden uprights 94 which I propose to place in the creel at suitable intervals. Each post has a pair 15 of wires 95 embedded in one face which are exposed at one or more gaps 96 for engagement by the bent outer end 97 of the lower arm 98 of a pivoted detector having an arm 99 resting on the yarn at a point where it is 20 supported by the bracket bearing the guide 21. In cases where my devices are applied to a warp, each yarn in the creel has a detector arranged to fall and close a gap in which the circuit in the magnet 85 is closed. An 25 annunciator 100 is located at a convenient point on the creel and serves to indicate approximately which yarn is broken.

The operation of the device is as follows:

A switch 101 serves to close the circuit to 30 an electro-magnet 85 (Figs. 3 and 6), so that a fallen detector completes the circuit and causes the magnet 85 to be energized. Thereupon armature 90 is raised releasing detent 77 which permits weighted lever 78 35 to drop and to pull down armature 82 at the same time releasing latch 74 and rock arm 71. The arm 71 is then free to swing to the right, being so swung by means of the weight 36 on the control lever 35 and the 40 arm 72 to the position shown in Fig. 8. As the parts assume the position shown in Fig. 8 the switch 101 is opened while the arm 71 lifts the lever 78 by means of the abutment 71' sliding along the lower faces of 45 the latch 74 and the lever 78, and the armature 82 is moved to the position to be held by magnet 83. The detent 77 is also moved into the position shown in Fig. 8. The control lever 35 is still in the full line position shown 50 in Fig. 8, but may be moved in counter clockwise direction by the operator without affecting the other parts, by reason of the pin and slot connection between arm 72 and link 73, thus returning rock arm 72 to 55 re-set position and closing the switch 101. Before the control lever 35 is returned to the position shown in Fig. 6, the broken yarn should be tied and the fallen detector replaced on the reunited yarn. As the control 60 lever 35 is rotated to the position shown in Fig. 7 the rock arm 71 returns to the position shown in Figure 6 and the device is in the re-set position for a gassing operation. The circuit of electro-magnet 85 being 65 broken by the raising of the fallen detector

the magnet will not be energized on the closing of the circuit at 101, and so trigger arm 91 will remain in position to hold detent 77 in the position of Fig. 8. When the arm 71 has moved counter clockwise the shaft 70 75 51' and the hand lever 52 move with it from the position of Fig. 5 to that of Figs. 2 and 4, thus moving the bar 47 to the left in Fig. 2, and swinging the burners down so as to turn off the gas. At such a time with the 75 treadle in the position of Fig. 8 the bar 41 is in the raised position of Fig. 2 and has turned the three-armed lever 43 against the resistance of its weighted arm 45 so as to cause pin 46 to engage in the notch in the 80 bar 47 locking the bar against return movement and locking the burners out of operation. After the broken yarn has been repaired the treadle is returned to the dotted line position in Fig. 8. The hand lever 52 85 90 will be returned from the position of Figs. 2 and 4 to that of Fig. 5, thus moving the bar 47 to the right in Fig. 2 and bringing the burners back into operative relation with the yarn. The hand lever 52 is rigidly 90 secured to the shaft 51'. It is therefore moved by the arm 71 as that arm is moved back from the position of Fig. 8 to that of Fig. 6. The magnet 83 being permanently 95 energized will tend to hold the armature 82 in the position clearly shown in Figs. 6 and 8 relieving the weight on the detent 77 and consequently the parts 80 and 78 will remain in the position of Fig. 6 until another 100 yarn failure occurs. The parts are locked 100 in this position by engagement of latch 74 with the abutment 71' on the rock arm 71 and by detent 77 in engagement with the arm 91.

It will be obvious to those skilled in the 105 art that various changes may be made in our device without departing from the spirit of the invention, and we, therefore, do not limit ourselves to what is shown in the drawings and described in the specification, 110 but only as set forth in the appended claims.

It will also be obvious that the machine of 115 my invention is not limited in use to the singeing of yarns, since various other yarn finishing and yarn handling operations may be carried on thereby, or by the use of features of the machine. Furthermore, fabric such as cloth or paper, or other continuous strip or strand material may be treated in various ways by the use of features of my invention, the term "yarns" 120 being used in the claims for convenience and not for limitation.

Having thus fully described my said invention, what I claim as new and desire to 125 secure by Letters Patent, is:

1. A gassing device for yarns including a valve casing, a pipe section coaxial with a part of the said valve casing adapted to oscillate relatively thereto for turning the 130

gas on and off, burners on the pipe section, a pilot burner fixed in relation to the other burners, and an auxiliary pipe section leading to said pilot burner, substantially as set forth.

2. A gassing device for yarns including a valve casing, a pipe section coaxial with a part of the said valve casing adapted to oscillate relatively thereto for turning the 10 gas on and off, burners on the pipe section, a pilot burner fixed in relation to the other burners, and an auxiliary pipe section leading to said pilot burner, said auxiliary pipe section oscillating with said first named pipe section and having a part coaxial therewith, substantially as set forth.

3. In a gassing device means for causing a set of yarns to travel together, a set of burners adjacent thereto, electrical stopping means including a constantly closed circuit, a normally open circuit, a control lever biased to move in a direction to stop the machine, means operated by said control lever for stopping travel of the yarn, means 20 for holding the said control lever in a position to allow the machine to operate, means operated by the first circuit for co-operation with the last named means to hold the control lever in position for operation of the machine, means controlled by the second circuit for releasing the control lever, and means for closing the second circuit on failure of a yarn, substantially as set forth..

4. In a gassing device means for causing a set of yarns to travel together, a set of burners adjacent thereto, electrical stopping means including a constantly closed circuit, a normally open circuit, a control lever biased to move in a direction to stop the machine, means operated by said control lever for stopping travel of the yarn, means 30 for holding the said control lever in a position to allow the machine to operate, means operated by the first circuit for co-operation with the last named means to hold the control lever in position for operation of the machine, means controlled by the second circuit for releasing the control lever, means for closing the second circuit on failure of a yarn, and means for breaking the second circuit after release of the control lever, substantially as set forth.

5. In a gassing machine means for causing a set of yarns to travel together, a set of burners adjacent thereto, electrical stopping means, including a constantly closed circuit, a normally open circuit, a control lever biased to move in a direction to stop the 40 machine, means operated by said control lever for stopping travel of the yarn, means for holding the said control lever in a position to allow the machine to operate, an electro-magnet in the first circuit, an armature therefor, gravity actuated means tend-

ing to move said armature away from the magnet, an electro-magnet in the second circuit, an armature therefor, a trigger arm controlled by said last named armature, the 50 said trigger arm operating to hold the gravity actuated means in elevated position, means for closing the second circuit on failure of a yarn, thereby energizing the electro-magnet in the second circuit to lift the second armature to allow the gravity operated means to disengage the means for holding the control lever in operative position, substantially as set forth.

6. In a gassing device means for causing a set of yarns to travel together, a set of 80 burners adjacent thereto, electrical stopping means including a constantly closed circuit, a normally open circuit, a control lever biased to move in a direction to stop the machine, means operated by said control 85 lever for stopping travel of the yarn, means for holding the said control lever in a position to allow the machine to operate, an electro-magnet in the first circuit, an armature therefor, means controlled by said armature 90 for co-operation with the last named means to assist in holding the control lever in active position said means including a rock arm, a latch for the rock arm, gravity controlled means for releasing the latch to release the 95 control lever said means also tending to free said armature from its magnet, an electro-magnet in the second circuit, an armature normally preventing operation of said 100 gravity controlled means, and means for energizing the second circuit on failure of a yarn, thereby energizing its electro-magnet to lift the second armature, said control lever on its way to idle position causing said rock 105 arm to restore the first armature to the field of attraction of its magnet, substantially as set forth.

7. A yarn treating device, comprising singeing means, independent detectors for the yarn, a circuit adapted to be closed by a fallen detector, a normally de-energized electro-magnet in the circuit, an armature therefor, a normally energized electro-magnet, an armature therefor, a weight adapted to pull the second armature from its magnet, a trigger controlled by the first named armature, a detent held by said trigger in position to prevent operation of said weight, part of the load of this weight being borne 110 by the normally energized electro-magnet, a control lever, a latch therefor, means operated by said weight to release the latch, a switch in the circuit of the first electro-magnet, and connections from the switch to a control lever whereby said circuit which 115 is closed by the fallen detector is again broken by the control lever in stopping the machine, substantially as set forth.

8. A gassing device comprising a bank of 120 burners, means to guide a sheet of yarns or 125

- the like over said burners, means whereby the burners may be turned about an axis extending transversely of said sheet to remove them from proximity to the yarn and 5 at the same time to cut off the flow of fuel from them, means for starting the flow of gas as the burners are returned to position under the yarns, and means for simultaneously relighting the gas, substantially as set forth.
9. A singeing warping machine, comprising means for guiding a series of yarns, a row of burners underneath said yarns, a slide connected to a bank of such rows, 15 means tending to oscillate the burners out of operative relation to the yarns, a rock shaft, an arm on the rock shaft connected to said slide, a latch acting on the rock shaft for holding the burners in operative position, means operative upon release of the latch for moving the said arm to move the burners to inoperative position and simultaneously to cut off the supply of fuel to the burners, and means for releasing the latch 20 on failure of a yarn, substantially as set forth.
10. A singeing warping machine, comprising means for guiding a series of yarns, a row of burners underneath said yarns, a slide connected to a bank of such rows, means tending to move the slide to oscillate the burners out of operative relation to the yarns, a rock shaft, an arm on the rock shaft connected to said slide, a latch acting 25 on the rock shaft for holding the burners in operative position, means for releasing the latch on failure of a yarn to permit the burners to be moved to inoperative position, and means for restoring the parts to operative position, substantially as set forth.
11. A singeing warping machine comprising means for guiding a series of yarns, a row of burners adjacent said yarns, a slide connected to a bank of such rows, a rock shaft, an arm on the rock shaft connected to said slide, a latch acting on the rock shaft for holding the burners in operative position, means tending to move the said arm to move the burners away from the yarns 45 detectors coacting with said yarns and a circuit closed by the movement of a detector, said circuit releasing said latch to permit the burners to be moved away from the yarn, substantially as set forth.
12. A singeing warping machine, comprising means for guiding a series of yarns, a row of burners underneath said yarns, a slide connected to a bank of such rows, a rock shaft, an arm on the rock shaft connected to said slide, means tending to move the arm to rotate the burners away from the yarns and to shut off the supply of fuel to the burners a latch acting on the rock shaft for holding the burners in operative 60 position, detectors on said yarns, a circuit closed by the fall of a detector, said circuit disabling said latch to permit the burners to be rotated away from the yarn, means for breaking the circuit when the burners are out of operation, and a treadle serving first to restore said circuit and then to permit the burners to move to operative position, substantially as set forth.
13. A singeing warping machine, comprising means for guiding a series of yarns, a row of burners underneath said series, means tending to oscillate the burners out of operative relation to the yarns, a latch for holding the burners in operative position, detectors coacting with said yarns, and a circuit closed by the movement of a detector, said circuit releasing said latch to permit the burners to move to inoperative position, substantially as set forth.
14. In combination, means for moving 85 yarns in the direction of their length, a control lever for said means, means for biasing the control lever to move in a direction to stop the yarn travel, a latch restraining the lever against such movement, means 90 tending to disengage the latch and said lever, a trigger arm engaging said last named means to prevent such disengagement, an electro-magnet for lifting said trigger arm, means for energizing said electro-magnet on failure of a yarn, an arm pivoted coincidentally with the trigger arm, connections from said arm to the latch moving means, electro-magnetic means tending 95 to hold the last named arm in elevated position, and means operated by the control lever for lifting said last named arm, the last named electro-magnetic means tending 100 to relieve the load on the said trigger arm in supporting the last named arm with its weight in elevated position, substantially as set forth.
15. In combination, means for moving 105 yarns in the direction of their length, a control lever for said means, means for biasing the control lever to move in a direction to stop the yarn travel, a latch restraining the lever against such movement, a weighted arm tending to disengage the said latch and said lever, a trigger arm engaging a detent 110 on said weighted arm to prevent such disengagement, means for lifting the said trigger arm on yarn failure, a second arm, means tending to hold said second arm in elevated position, connections between said 115 weighted arm and said second arm, said second arm assisting the said trigger arm in supporting the said weighted arm, and means operated by the control lever for resetting said weighted arm and returning said second 120 arm to elevated position, substantially as set forth.
16. In combination, means for moving 125 yarns in the direction of their length, a control lever for said means, means for biasing 130

the control lever to move in a direction to stop the yarn travel, a detent restraining the lever against such movement, means to release the detent on yarn failure, and means 5 operated by the control lever in its stopping movement for resetting said detent, substantially as set forth.

17. In combination, means for moving 10 yarns in the direction of their length, a control lever for said means, means for biasing the control lever to move in a direction to stop the yarn travel, a latch restraining the lever against such movement, impact means to release the latch on yarn failure, a trigger 15 for holding the impact means in set position, and means operated by the control lever for moving the impact means to position to be held by the trigger arm, substantially as set forth.

18. In combination, means for moving 20 yarns in the direction of their length, a control lever for said means, means for biasing the control lever to move in a direction to stop the yarn travel, a latch restraining the lever against such movement, impact means 25 for releasing the latch, a detent on said impact means, a trigger arm for engaging said detent for holding the impact means out of action, means to withdraw the trigger arm on yarn failure, and means operable by the 30 control lever for moving the detent for engagement by the said trigger arm, substantially as set forth.

In witness whereof, I have hereunto set my hand at Chattanooga, Tennessee, this 6th 35 day of March, A. D. nineteen hundred and twenty-five.

DAVID GRAVEL.
